Charles A. Magoon, Riverdale, Md.

Application February 9, 1934, Serial No. 710,535

5 Claims. (Cl. 41—36)

(Granted under the act of March 3, 1883, as
amended April 30, 1928; 370 O. G. 757)

This application is made under the act of March 3, 1883, as amended by the act of April 30, 1928, and the invention herein described, if patented, may be manufactured and used by or for the 5 Government for governmental purposes without the payment to me of any royalty thereon.

This invention relates to illustrations and pictures produced by the utilization of the dusts of various species of wood, which because of their 10 very considerable variation in colors constitute a unique medium for artistic expression.

The subject matter hereof is illustrated in the accompanying drawing in which Figure 1 is a plan view of a picture executed in accordance 15 with the invention and Figure 2 is an edge view thereof. Conventional linings or hatchings are utilized in the drawing to represent various colors.

The dusts used in making such pictures are preferably derived from woods and barks of various 20 species of trees and shrubs in the form of naturally colored dusts such as sawdust, products of abrasive operations such as sanding, or as powdered residues of grinding and pulverizing operations. These dusts because of the different and 25 particularly harmonious colors of the woods and barks used, and the variation in fineness of the particles, yield a wide range of colors and constitute an unusual means for making artistic designs. It may be observed that different parts 30 of the same tree or shrub, such as the heart, knots, etc., yield a variety of colors. While the range of natural colors in wood dusts is large and particularly attractive, the range of color may be vastly extended by supplying the colored 35 dusts in part from artificially colored woods and artificially colored dusts. As indicated above, it is found that the color of dusts from the same piece of wood vary as a consequence of the fineness of the particles.

40 In carrying out my invention there is provided a base or a foundation background 1 of such material as canvas, fibre-board, wood, glass or metal upon which the picture, design or illustration is to be produced. The design or picture 45 may be sketched upon the base material, although this step may be omitted, its necessity being dependent on the skill of the workman. A coating of an adhesive substance 2 such as gums, silicates, dextrines, etc., is applied with a brush, 50 atomizer or other suitable means to one surface of the base material 1 or to such portion thereof as is covered by a particular design, and wood dusts in different colors 3 appropriate to the picture, illustration or design to be produced are applied to the base 1 and adhesive 2. The adhesive 55

utilized should preferably possess germ resisting, 5 germicidal or antiseptic properties. The wood dusts 3 should be applied carefully with the fingers, tweezers, brush, or any convenient implement, following the plan of illustration or decoration dictated by the design to be produced. The colors of course, are selected in accordance with the artistic views of the artist and the effects desired.

The use of wood dusts in natural colors produces a particularly pleasing artistic picture of 10 distinctive character. The colors are extremely harmonious and soft and the picture possesses a tapestry like appearance entirely different from that secured through the use of oil paints and 15 water colors. While colored pictures may be produced with naturally colored wood dusts exclusively, artificially colored wood dusts may be used entirely or desired colors not available otherwise 20 may be supplied and used in conjunction with natural wood dusts. The tapestry-like appearance is present in the pictures without regard to whether naturally or artificially colored wood dusts are used. Bas relief or three-dimensional effects are secured by cumulative additions of 25 wood dusts, additional adhesive substance to be used to the extent necessary.

The wood dust 3 may be arranged on the base or background 1 with a flat stick. The dust may be deposited lightly on the background or compacted with the stick to produce desired effects and distinct lines of color may be formed with the edge of the stick. After the design or picture 30 is complete in a manner satisfactory to the artist it may be protected from deterioration and 35 injury by applying a coating of shellac, picture mastic varnish, or other colorless protective adhesive material applied with a brush, air-brush, atomizer or other suitable means.

Having fully disclosed my discovery, I claim: 40

1. As an article of manufacture, a colored pictorial illustration which comprises a base, naturally colored wood dusts from different species of trees and shrubs adhesively mounted in definite picturization on the base, the particular wood 45 dusts and the arrangement thereof being dictated by the subject matter of the illustration, whereby the colors of the illustration are produced in wood dusts of different colors.

2. As an article of manufacture, a colored pictorial illustration which comprises a base, naturally colored wood dusts from different species of trees and shrubs adhesively mounted in definite picturization on the base, the particular wood 50 dusts and the arrangement thereof being dictated 55

by the subject matter of the illustration, whereby the colors of the illustration are produced in wood dusts of different colors and a coating of a transparent adhesive protective material on the wood dust.

5 3. As an article of manufacture, a colored pictorial illustration which comprises a base, naturally colored wood dusts adhesively mounted in definite picturization on the base, and a coating of a transparent adhesive protective material on the wood dust.

10 4. As an article of manufacture, a colored pic-

torial illustration which comprises a base, naturally colored wood dusts adhesively mounted in definite picturization on the base, and a coating of a transparent adhesive protective material on the wood dust.

5 5. As an article of manufacture a colored pictorial illustration which comprises a base, naturally and artificially colored wood dusts adhesively mounted in definite picturization on the base.

CHARLES A. MAGOON. 10
